RAILWAY TRUCK

Donald S. Barrows, Rochester, N. Y., assignor to
 The Symington-Gould Corporation, Rochester,
 N. Y., a corporation of Maryland

Application November 18, 1936, Serial No. 111,511

33 Claims. (Cl. 105—190)

This invention relates to railway vehicles and, more particularly, to trucks in which the parts are flexibly connected, one with another, so that the bolster is permitted to move laterally with respect to a supporting transom, and the side frame is permitted to angle with respect to said transom and associated journal boxes.

The principal object of my invention, generally considered, is to improve the construction of railway trucks, and particularly that of the bolsters, supporting transoms and associated parts, in order to allow for adjusting movement between the bolsters, transoms, side frames and journal boxes.

Another object of my invention is the provision of a railway truck of improved form, and preferably including the features of having the frames of "double truss" construction with the omission of spring planks, the relationship between the transoms and guide columns including cylindrical wearing surfaces to provide the desired flexibility, and the employment of separate journal boxes, including the same cylindrical feature, helical and elliptic springs being used between the journal boxes and the ends of said frames as well as for supporting the transom. The bolster is inverted U-shape in section and fits over the supporting transom, being swingably supported therefrom, to allow for the desired lateral movement of the bolster with respect to the transom.

A further object of my invention is the provision of a railway truck in which the frames are connected by a spring-supported transom and, if desired, also by a bottom tie rod hingeably connected to each side frame, said rod replacing the usual form of spring plank, said transom carrying a bolster having depending side flanges embracing the major portion of the transom and connected thereto by means of swing links hanging from the ends of keys, the central portions of said keys having their lower surfaces extended to form rockers preferably engaging curved wear blocks mounted in the transom. Relatively short links are utilized to connect the bolster and transom, and by reason of the introduction of rolling action between the key rocker portions and the wear blocks on the transom the swing motion of the bolster for a portion of its movement is in an arc, the radius of which is much greater than the actual length of the supporting links.

A still further object of my invention is the provision of a compound bolster construction including a relatively long bolster part supported

from associated side frames by means of springs, and a relatively short bolster part of generally hollow construction, including flanges embracing the major portion of the relatively long bolster part, said relatively long bolster part having keys rockably mounted therein with ends extending from opposite sides thereof, said key ends carrying swing links which, in turn, carry the relatively short bolster part for lateral movement with respect to the relatively long part.

Other objects and advantages of the invention, relating to the particular arrangement and construction of the various parts, will become apparent as the description proceeds.

Referring to the drawings illustrating my invention, the scope whereof is defined by the appended claims:

Figure 1 is a fragmentary side elevational view of one embodiment of my truck, portions being shown in vertical section.

Figure 2 is a transverse sectional view on the line 2—2 of Figure 1, looking in the direction of the arrows, portions of the associated bolster, transom and supporting springs being shown in side elevation.

Figure 3 is a fragmentary horizontal sectional view of the frame on the line 3—3 of Figure 1, looking in the direction of the arrows, the bolster springs being shown in plan.

Figure 4 is a fragmentary horizontal sectional view of the frame, on the line 4—4 of Figure 1, looking in the direction of the arrows, portions of the transom and supported lateral motion bolster being illustrated in plan.

Figure 5 is a fragmentary sectional view on the line 5—5 of Figure 1, looking in the direction of the arrows.

Figure 6 is a fragmentary sectional view of the transom and supported bolster on an enlarged scale on the line 2—2 of Figure 1, looking in the direction of the arrows.

Figure 7 is a fragmentary sectional view on the line 7—7 of Figure 6, looking in the direction of the arrows.

Figure 8 is a diagram, showing the manner of securing the effect of long swing links, by introducing rolling action into the mounting of the bolster-supporting keys.

Referring to the drawings in detail, like parts being designated by like reference characters, there is shown a portion of a truck 1 comprising a pair of side frames 2, only one of which is illustrated. Each side frame comprises a compression member 3, a tension member 4, and bolster guide columns 5, spacing intermediate portions 55

of said compression and tension members, and spaced to leave a bolster or window opening 6 therebetween. Each frame has downwardly opening pockets or jaws 7, only one of which is illustrated, at the ends thereof for receiving journal boxes 8.

The compression member 3 preferably comprises a web 9, which extends outwardly to overlie each journal box 8, and flanges 10 depending from the sides thereof. The tension member 4 has an intermediate normally horizontal spring-supporting portion 11, generally box-shaped in section, the upper web 12 of which is extended laterally, beyond depending flanges or substantially vertical web portions 13 thereof, to provide a spring-supporting portion of adequate area.

The spring-supporting portions, beyond the flanges 13, are desirably reinforced by triangular gussets 14. The depth of the flanges 13, along the diagonal end portions of the tension member, is generally less than that of said flanges of the horizontal portion thereof, the lower outline of said diagonal portions being desirably first concave downwardly and then convex downwardly, to provide a bulge beneath the guide columns where the diagonal portions join the horizontal portions, thereby reinforcing the junctions at the guide columns. The lower web portion 15, beneath the bolster opening 6, desirably terminates beneath the guide columns, leaving the outer portions of the tension member substantially inverted U-shape in section.

The side frame being desirably of the "double truss" type, in the present embodiment, I show the upper web 12 of said member formed with upper longitudinal convolutions or corrugations 16, which provide auxiliary web portions disposed at an angle to, and merging into, the main web 12. These auxiliary web portions, which are connected to the main web portion by generally triangular side portions 17, as shown in Figure 3, start between the guide columns and extend diagonally upward and outward through said columns, to finally merge with the normal plane of the web 12 at approximately the point where the depending flanges 10 of the compression member join said web 12, thereby strengthening the angle between the horizontal and inclined portions of the tension member, as well as providing supplemental or intermediate support for those portions of the tension member between the guide columns. The portions of the upper web 12, beyond the flanges 13, desirably taper beneath the guide columns to finally merge into the flange portions 13 at approximately the bases of the columns 5, as shown most clearly in Figure 1.

Each guide column 5 desirably comprises a web portion 18, which extends substantially vertically along the guiding portion thereof. The sides of the guide columns are defined by flange portions 19, extending from the side edges of the web 18, with their free edges preferably reinforced by beading 20. Said flanges are desirably spaced a greater distance than the width of the convolutions 16 in the tension member, so that they straddle said convolutions and connect with the main web portions 12 of the tension member on either side of the convoluted portion thereof.

In the present embodiment, I provide for connections between the inner bolster member, of a two-part or multi-part bolster, or transom 21 and the side frames 2 which correspond some-

what with the bolster-frame connections shown in my application Serial No. 629,953, filed August 22, 1932, which has since matured into Patent No. 2,132,381, granted October 11, 1938. For that purpose the flanges 19 at the bolster guiding portions of the guide columns 5 are formed with outer guiding surfaces 22 disposed on planes radial, or substantially radial, from the vertical axis 23, or the line of intersection between the central longitudinal and central transverse planes of said frame. The bolster has flanges or lugs 24 formed on corresponding radial planes for engagement with the guiding surfaces 22 on the columns, the included angle between said surfaces being greater than the included angle of the radial column sides by an amount equal to the angle which the bolster is permitted to swing from one extreme to the other upon departure from the normal right angle relationship with respect to the frame.

Instead of forming the webs 18 of the guide columns with their inner surfaces on parallel planes, I have formed said inner surfaces concave to correspond with a vertically disposed cylinder whose vertical axis coincides with the axis 23 of the frame, and the bolster or transom 21 has its side webs 25 bulged, as shown most clearly in Figure 4, so that the outer surfaces thereof fit the concave cylindrical inner surfaces of the webs 18 of the guide columns, thereby allowing for angling between said bolster and frames, with the avoidance of line contact upon reaching the limits of angling. The upper and lower webs of the bolster or transom 21 are desirably reinforced by a connecting web 26, as shown most clearly in Figure 1.

I show the bolster or transom 21 supported from the illustrated frame by means of a nest comprising four helical springs 27 and two elliptic springs or sets of banded leaf springs 28, without the use of a spring plank. The nest of coil and elliptic springs is desirably provided with upper and lower spring plates 29 and 30, which may take a form such as generally described in one of the Townsend applications Serial No. 694,332, filed October 19, 1933, which has since matured into Patent No. 2,084,543, granted June 22, 1937, and Serial No. 704,958, filed January 2, 1934, which has since matured into Patent No. 2,102,102, granted December 14, 1937, although I do not wish to be limited to this construction. However, in order to more accurately maintain the plates in proper position with respect to the frame, the lower plate 30 desirably has upstanding lugs 31 disposed in positioning relation with respect to upstanding lugs 32 on the spring-seating portion of the tension member web 12, as shown most clearly in Figure 3. In this way the positioning of the lower spring plate is not dependent on its nesting over the corrugations 16, which is not ordinarily a tight fit. For uniformity and economy in manufacture, both spring plates of both frames are desirably of the same construction. The springs are thus held in the desired relation with respect to one another, and the complete nest is held in the desired relation with respect to the associated side frame and bolster.

The omission of the spring plank is desirably partly compensated for by a tie bar or rod 33 which desirably connects the frame to the associated frame (not shown) at the other side of the truck, the connections being flexible, as by means of a pin 34 passing through an eye 35 on each end of the tie rod 33 and corresponding

lugs 36, upstanding from the web 12 of the tension member 11.

In order to increase the flexibility of the truck and allow for lateral motion of a supported car body (not shown) with respect to the supporting side frames, I employ a bolster 37 or relatively short part of a two-part or multi-part bolster, with the frame-connecting relatively long part or transom 21, said bolster 37 carrying the usual truck center plate portion 38 and being mounted on the transom 21 for lateral motion with respect thereto. The means for supporting the bolster 37, which comprises an upper web 39 and flanges 40 depending from the sides thereof and straddling the transom 21, includes a key 41 intersecting the transom 21 adjacent each end thereof, each key having its ends extending beyond the sides of said transom and movably supporting a link 42, by extending through slots 43 therein. The lower portion of each link 42 receives a relatively short pivot pin 45, the ends of which are received in the adjacent flange 40, and an adjacent intermediate bolster flange 46. If desired, removal of the pins 45 is prevented by notching the outer end of each, as indicated at 47, allowing said notched portions to engage webs 48, partially closing the apertures or pockets 49 which receive the outer ends of the pins 45. Inward movement of the pins 45, after assembly of the lateral motion bolster 37 with the transom 21, is prevented by the adjacent side wall portions of the transom, as shown most clearly in Figure 7.

If the top of each link 42 were pivoted for rotation about a fixed axis on the transom 21 and the lower end of each link were pivoted for rotation about an axis fixed with respect to the lateral motion bolster 37, a given amount of lateral motion of said bolster 37 with respect to the transom 21 would result in a relatively large amount of upward movement of said bolster 37 with respect to the associated transom 21, the actual amount depending on the length of the links 42 which, in accordance with my invention, are relatively short. In order to provide for a relatively easy or slow upward movement of the bolster 37, upon lateral movement thereof with respect to the supporting transom 21, I form the lower edge 50 of the intermediate portion of each key 41 with a curved surface, as shown most clearly in Figure 6, thereby providing for rocking action of said key.

In order to minimize wear on the supporting transom 21, I desirably position a plate 51 directly beneath the rocker portion 50 of each key 41, each wear plate having its key-engaging surfaces struck on an arc of relatively easy curvature, as shown in Figure 6. Said plate may be maintained in position in any desired manner as by providing depending end flanges 52 received in corresponding outer notches 53 in the side surfaces of said transom, as shown most clearly in Figure 7. The slots 43 receiving the ends of the key 41 are elongated laterally, so that upon lateral movement of the bolster 37, each link 42 pivots about the center of the radius of the top surface of the key 41, while the key rocks in the direction of lateral motion, thereby effectively elongating the radius of curvature about which the links 42 rotate, as shown diagrammatically in Figure 8.

As an example of an embodiment of my invention, if we consider links of approximately seven and three-fourths inches in length pivoted about a key 41 which, during link pivoting, rolls from

the median position, indicated in full lines in Figure 8, to the dotted positions 41' in one direction and 41'' in the other direction, as shown, the real radius of rotation of each link is approximately twenty-four and one-half inches, rather than seven and three-fourths inches, because of the rolling progression of the key 41 as the links 42 rotate about the upper surface thereof. This results in a very easy lateral motion effect, while avoiding clearance difficulties which might arise if long links were employed.

When the keys 41 have rocked to either of the positions 41' or 41'', further movement of the keys in the same direction is prevented by the engagement between them and the adjacent portions of the transom, and a further movement of the bolster in the same direction will therefore follow an arc, the radius of which is equal to the length of the links 43. The final movement of the bolster is therefore resisted by the sharp increase in the work performed, due to the greater gravitational resistance to the movement of the bolster on this relatively short radius.

Assembly of the lateral motion bolster 37 with respect to the transom 21 is effected after the pins 45 have been positioned, to hold the links 42 in place in the pockets between the flanges 40 and 46, whereupon the bolster 37 is fitted over the transom 21, which transom, of course, has the wear plates 51 in place, whereupon the keys 41 are positioned through the apertures 54 in the flanges 40 before the bolster 37 is lowered to its final position, as shown in Figure 7. After reaching this final position, as illustrated, the flanges 40 defining the apertures 54 extend below the upper edges of the keys 41 and prevent undesired removal or displacement thereof. After assembly the bolster 37 is prevented from undesired upward displacement with respect to the transom 21 by means of bolts 55 connecting depending lug portions of the depending intermediate flanges 46 and encircled by spacing sleeves 56. The bolts may be headed at one end, as indicated at 57, and each receives a nut or other securing device 58 at the other end. The sleeves 56 may have sufficient clearance, and be so close to the lower surface of the transom 21, as shown in Figure 6, that the bolster cannot be raised sufficiently with respect to said transom, when the bolts 55 are in place, to allow withdrawal of the associated keys 41. The relative movement between the bolster and transom is limited by the contact of the shoulders *a* and *b*, shown most clearly in Figure 4.

The bolster 37 not only carries the center bearing 38, but may also have a raised portion 57' of its upper web 39 above each transom portion which receives a key 41, which is adapted to serve for the support of a side bearing (not shown).

In order to provide an extra cushioning effect between the journal boxes 8 and the transom 21, to further dampen out vibrations and cushion shocks transmitted to the supporting wheels from the track on which they travel, I provide a set of springs between each journal box and the associated end of each frame, each set in the present embodiment comprising two helical springs 59 and one semi-elliptic or banded leaf spring 60 and, therefore, having a period of vibration different from that of the bolster springs. Other forms of non-harmonic springs could, of course, be used in this location.

Each helical spring 59 desirably engages an outstanding ledge 62 at the side of its box and is retained in place by a peripheral flange 62' 78

upstanding therefrom to provide for centering said spring. The ledges 62 are desirably disposed substantially at the level of the box centers and journal (not shown) received therein, as illustrated. The encircling flanges are desirably cut low enough at one portion to facilitate application and removal of the springs 59, being, however, continued upwardly to provide gussets 63 extending between the sides of the ledges 62 and 10 the sides of the boxes 8, said flanges or gussets being desirably cylindrical so as to partially house the springs, as will be seen from Figure 5, and extending into the space at the inwardly convoluted sides of the box which provide the brass lugs 64, 15 the flanges at their inner ends desirably merging with said brass lugs, as illustrated.

In addition to the cylindrical surrounding flanges 63, I desirably bulge the sides of each box outwardly, as indicated at 65, to provide portions merging with intermediate portions of the flanges 63, and cylindrically coaxial with the vertical axis of the box 8, which portions cooperate with flanges 66 partially defining the jaws 7 which receive the journal box. The flange portions 66 are joined by web portions 67 which extend around the outer portions of the cylindrical webs or flanges 62 and 63 and complete the enclosure of the springs 59 by box and frame portions. The upper portions of the flanges and webs 66 and 67 are connected by web or abutment portions 68 which overlie the ledges 61 and provide upper spring-engaging surfaces.

Each semi-elliptic spring 60 desirably has its band or central portion 69 engage a projection 10 from the top of a journal box 8, said projection being desirably formed with parallel upstanding beading or ribbing 71 providing a pocket to receive said spring band 69 and prevent undesired displacement thereof. Each projection 40 70 extends through a corresponding aperture 72 in the web portion 68 of the frame which connects the abutment portions 68, said aperture 45 guidingly receiving said projection 70, but being large enough to provide the desired clearance for allowing relative angling of the box 8 with respect to the frame about the vertical axis of the box, as provided for by the cylindrical portions 65 and 66. The ends of the semi-elliptic springs 60 engage abutments 73 and 74, respectively, provided adjacent the end of the compression member web 9 and intermediate the ends of said web.

The upper web 12 of the tension member extends outwardly beyond the junction with the compression member, but terminates short of the 55 web of the compression member, as shown in Figure 1, in order to avoid interference with the semi-elliptic spring 60, the web for that purpose being desirably bifurcated, as indicated at 75, with the separated portions tapering to gradually merge into the sides of the frame. The 60 inner spring or abutment portions 68 are desirably connected at their inner ends to, or branch from, the extended web 12, as indicated at 76. In order to strengthen the frame adjacent the 65 spring housings 63, the lower edges of the flanges 13 are provided with outwardly projecting flanges 61 clearly shown in Figure 1.

In order to hold the springs 59 and 60 under initial tension, if desired, and prevent undesired 70 removal of the boxes from the frame, said boxes are desirably secured in place by locking means which, in the present embodiment, take the form of retainer bolts 77, the ends of which pass through depending lug portions 78 on the frame, 75 and the intermediate portions of which underlie

the ledges or spring-engaging webs 62 of the boxes. Loss or undesired removal of said bolts may be prevented in any desired manner, as by means of nuts and/or cotters (not shown).

To prevent the rapid wear of the adjacent portions of the transom and bolster, there are preferably provided wear plates 79 and 80 removably attached to the transom and bolster respectively in overlapping relation so as to afford engaging surfaces throughout the entire range of relative 10 movement between the bolster and transom.

From the foregoing description, taken in connection with the accompanying drawings, it will be seen that I have devised a truck involving side frames of a preferred form and adapted to be 15 connected to and disconnected from an associated transom and lateral motion bolster, as well as associated journal boxes, said transom and boxes, in the engaging portions of said frames, being so constructed that a limited amount of 20 horizontal angling therebetween is permitted, with the maintenance of contacting areas of substantial extent regardless of relative angularity. It will also be seen that I have provided non-harmonic groups of springs not only for supporting 25 the transom or relatively long bolster member from the side frames, but also for supporting the frames from the boxes.

If, because of the short travel of the journal box springs and their period of high frequency, 30 the matter of synchronization of these particular springs is not found to be of serious consequence, then three coils could be used for each box instead of two coils and a semi-elliptic spring, because the bolster spring group, through which 35 the entire load passes, is fully non-harmonic. It might be added that while the nest of bolster-supporting springs desirably has a full standard bolster spring travel of one and eleven-sixteenths inches, the nest of springs for each journal box 40 need only have a travel of about one inch.

The flexibility of the truck, due to the provision for horizontal angling between each frame and its associated journal boxes and transom, is further enhanced by the provision of the relatively short bolster 31 which straddles the transom 21 and is adapted to move laterally with respect thereto, swinging therefrom on links with the provision for rocking between the link-supporting keys and the associated transom. While 45 relatively short links may be employed, the effect of considerably longer links is ensured by the rocking motion of the keys as they follow the swinging motion of the links in one direction or another, in accordance with the motion of the 50 supported bolster.

Although a preferred embodiment of my invention has been disclosed, it will be understood that modifications may be made within the spirit and scope of the appended claims and that substitutions may be made; for example, a full elliptic or other form of leaf spring may be substituted for the semi-elliptic springs shown.

While throughout the specification and the appended claims I have used the words "transom" 65 and "bolster" interchangeably, it is to be understood that by "transom" or "transom-bolster" I refer to the spring-supported portion of my two-part or multi-part bolster and do not intend to be limited to or to imply, as is usual with transoms, a part which extends from one side frame to the other and is rigidly connected to each. The spring-supported portion of my bolster or transom-bolster has its end portions slidably mounted between the bolster column guides of 70 75 76

the side frames and is yieldingly supported therein by a nest of springs carried by the spring seat portion of the side frame.

I claim:

5. 1. In a car truck, the combination with a side frame having tension and compression members and interposed struts forming bolster guide columns, of a bolster comprising a spring-supported portion adapted to extend between said guide columns and slidably supported therein by a nest of springs and a car-body-supporting portion, and means for swingably supporting said last-named portion on said spring-supported portion, said means comprising a plurality of pairs of links, each pair of links being rotatably mounted on ends of keys, said keys being rockably mounted and extending through apertures in said spring-supported portion.
10. 2. In a car truck, the combination with a side frame having tension and compression members and interposed struts forming a bolster opening, of a two-part bolster, one portion of which extends between said bolster guide columns and is slidably supported therein by a nest of springs carried by said side frame, said other portion comprising a car-body-supporting portion, said last-named portion terminating short of said side frame and swingably supported from said first-named portion by a plurality of pairs of links, each pair of links being interposed between side walls of said portions and rockably and rotatably mounted on said spring-supported portion of the bolster.
15. 3. In a car truck, the combination with a side frame having tension and compression members and interposed struts forming bolster guide columns, of a bolster comprising a spring-supported portion adapted at its end to extend between said guide columns and slidably supported therein by a nest of springs carried by said frame, and a car-body-supporting portion of substantially inverted U-shape in section and partially enclosing the adjacent portion of said spring-supported portion, each end of said car-body-supporting portion being supported from said spring-supported portion by a pair of links, the links of each pair being pivotally connected adjacent their lower ends to said car-body-supporting portion and being pivotally connected to keys adjacent their upper ends, said keys being rockably associated with said spring-supported portion.
20. 4. In a car truck, the combination with a side frame having tension and compression members and interposed struts forming bolster guide columns, of a bolster comprising a spring-supported portion adapted at its end to extend between said guide columns and slidably supported therein by a nest of springs carried by said frame, and a car-body-supporting portion of less length than said first-named portion and of substantially inverted U-shape in section, said car-body-supporting portion being provided at each end with inner and outer depending flanges, a link pivotally supported adjacent its lower end between each pair of adjacent flanges, and means carried by said spring-supported portion for pivotally and rockably supporting said links adjacent their upper ends.
25. 5. In a car truck, the combination with a side frame having tension and compression members and integral interposed struts forming bolster guide columns, of a transversely extending bolster member comprising a spring-supported portion adapted to extend between said guide col-

umns and slidably supported therein by a nest of springs carried by the side frame and a car-body-supporting portion, and means for swingably supporting said last-named portion on said spring-supported portion, said means comprising a plurality of pairs of links, each pair of links being connected adjacent its lower ends to said car-body-supporting portion, and each pair of links being pivotally and rockably supported adjacent its upper ends upon a key extending outwardly of and carried by said spring-supported portion.

6. In a car truck, the combination with a side frame having a bolster opening, of a two-part bolster, one of said parts having an end received in said bolster opening and provided adjacent the inner face of said side frame with a key, springs supporting said bolster part from said side frame, a second bolster part with its end terminating short of said frame and supported on said first-named part by links depending from the ends of said key, said second bolster part having a pair of flanges at each side of said first-named bolster part, one of said links being received between each pair of flanges, said flanges being apertured to permit the insertion or removal of said key, said apertures in the outer flanges being out of line with the apertures in the inner flanges when the parts are in assembled position so as to prevent accidental displacement of said key.

7. In a car truck, the combination with a side frame having a bolster opening, of a bolster, springs supporting said bolster from said frame, said bolster being in two parts and comprising a spring-supported portion and a shorter portion inverted U-shape in section and partially enclosing said spring-supported portion, each end of said shorter portion comprising a pair of spaced depending flanges lying adjacent each side of said spring-supported portion, a key adjacent each end of and extending through apertures in said spring-supported portion and the inner flanges of said shorter portion, but terminating short of said outer flanges, and links depending from the outer ends of said keys and disposed between said spaced flanges, the lower ends of said links receiving pins the ends of which are received in corresponding apertures in said spaced flanges.

8. In a railway car truck, the combination with a pair of side frames, each having a bolster opening, of a two-part bolster with its ends received in said opening and yieldingly supported therein by springs carried by said side frames, a second bolster part of inverted U-shape in section mounted on and partially enclosing said first-named part, each end of said last-named part comprising a pair of spaced depending flanges lying adjacent each side of said first-named part, a key adjacent each end of and extending through said first-named or spring-supported part, a bearing member housed within said spring-supported part and disposed beneath each key, the lower surface of each key engaging said bearing member for rocking movement thereon, links pivotally mounted on the opposite ends of each key and each depending between a pair of adjacent flanges on said second-named bolster part, and pins extending through apertures in each pair of flanges on said second-named bolster part for pivotally connecting each link adjacent its lower end to said second-named bolster part.

9. In a car truck, a two-part bolster comprising an inner and an outer bolster part, the inner bolster part having its end portions received be-

tween the bolster guide columns of a pair of side frames and being spring-supported thereon, the outer part being adapted to support the car body and being pivotally mounted upon said inner part by means of a plurality of pairs of links; a key having a rocking bearing on the inner part of said bolster and being pivotally connected to the upper ends of an adjacent pair of links, the opposite ends of said links being pivotally connected to 10 said outer bolster part, and means on said inner bolster part to limit the rocking movement of said key beyond a predetermined distance.

10. In a car truck, the combination with a pair of side frames having bolster openings formed 15 therein, of a transom-bolster having its ends received within said openings and being slidably supported therein for vertical movement by springs carried by said side frames, of a swing motion bolster of less length than said transom- 20 bolster supported on said transom-bolster by a plurality of pairs of links, the lower ends of each pair of links being pin connected to the swing motion bolster and a key for rockably and pivotally connecting the opposite ends of each pair of 25 links to the transom-bolster, and means on said transom-bolster for limiting the rocking movement of said keys whereby the lateral thrust from said swing motion bolster is transmitted to said transom-bolster substantially within the body 30 thereof.

11. In a railway truck, in combination, a side frame having a bolster opening, a transom-bolster with an end received in said opening, springs supporting said transom-bolster from said frame, 35 a lateral motion bolster supported by and partially enclosing said transom-bolster, each end portion of said lateral motion bolster comprising a pair of spaced depending flanges lying adjacent each side of said transom-bolster, a key adjacent 40 each end of and extending through apertures in said transom-bolster and the inner flanges of said lateral motion bolster, but terminating short of said outer flanges, whereby said key is held in place, the lower surface of said key, between the 45 sides of said transom-bolster, being curved to provide for rocking therebetween, links depending from the outer ends of said keys and disposed between said spaced flanges, and pins passing through apertures in the lower ends of said links 50 and with their ends extending into apertures in the corresponding spaced flanges.

12. In a railway truck, in combination, a pair of side frames, each having a bolster opening, a transom-bolster with its ends received in said 55 openings, springs supporting said transom-bolster from said frames, a swing motion bolster of inverted U-shape in section supported from said transom in straddling relation therewith, keys extending through said transom-bolster and 60 rockably mounted thereon, and links rotatably mounted on the ends of said keys, other portions of said links also being rotatably connected with said swing motion bolster for allowing lateral movement thereof, and means for retaining said 65 last-named bolster in place on said transom-bolster comprising bolts connecting depending lug portions on said swing motion bolster and underlying said transom-bolster.

13. In a railway truck, the combination with a 70 pair of side frames each having a bolster opening, of a transom-bolster with its ends received in the respective openings and spring-supported from said frames, said transom-bolster being adapted to move vertically in said bolster openings with 75 substantially no longitudinal movement with re-

spect to said frames, and a lateral motion bolster with its ends terminating short of said frames and having an upper web carrying center and side bearings, and side flanges depending from the edges of said web and receiving said transom-bolster therebetween, said lateral motion bolster being suspended through said transom-bolster, with the provision for lateral motion, by keys extending through said transom-bolster and rockably mounted with respect thereto, the ends of 10 said keys carrying links and the lower ends of said links being pin-connected with respect to said depending flanges.

14. A flexible railway truck comprising a pair of side frames connected by a transom-bolster 15 supported therefrom and said frame also being supported by journal boxes, each frame having guide columns with interior faces cylindrically concave about the vertical axis of said frame, said transom-bolster having end portions received between said guide columns and formed with outer cylindrically convex surfaces cooperating with said concave surfaces for angling therebetween, each journal box having side walls bulged to form outer surfaces cylindrically convex about its vertical axis, and said side frame having pockets, 20 defined by cylindrically concave surfaces, cooperating therewith for holding said boxes in place while allowing angling therebetween in a horizontal plane, springs supporting said frames from 25 said boxes and said transom-bolster from said frames, and a swing motion bolster fitting over said transom-bolster and suspended therefrom by means of links mounted on the ends of keys 30 extending therethrough, whereby said swing motion bolster has freedom of movement laterally with respect to said frames and said frames have freedom of movement for angling with respect to 35 said transom-bolster and associated journal boxes.

15. A flexible railway truck comprising a pair of side frames connected by a transom-bolster spring-supported therefrom, journal boxes slidably mounted on said side frames, springs interposed between said frames and each journal box, 45 each frame having guide columns with interior faces cylindrically concave about the vertical axis of said frame, said transom-bolster having end portions received between said guide columns and formed with outer cylindrically convex surfaces 50 cooperating with said concave surfaces for angling therebetween, each journal box having side walls bulged to form outer surfaces cylindrically convex about its vertical axis, and each of said side frames having a plurality of pockets 55 each defined by cylindrically concave surfaces cooperating with the said faces of one of said journal boxes for holding said boxes in place, while allowing angling between each box and its associated side frame in a horizontal plane, and a 60 lateral motion bolster fitting over said transom-bolster and suspended therefrom by means of links mounted on the ends of keys extending therethrough, said keys having a limited rolling action with respect to said transom-bolster as the 65 links rotate about their free ends, thereby elongating the effective radius of rotation of said links and permitting greater freedom of lateral movement of said lateral motion bolster.

16. A flexible railway truck comprising a pair 70 of side frames the tension members of which are connected by a tie member pivoted to each frame, a transom-bolster each end of which is spring-supported from an adjacent frame, journal boxes slidably mounted on said side frames, 75

5 springs interposed between said frames and each journal box, each frame having guide columns with interior faces cylindrically concave about the vertical axis of said frame, said transom-
 5 bolster having end portions received between said guide columns and formed with outer cylindri-
 cally convex surfaces cooperating with said concave surfaces for angling therebetween, each journal box having side walls bulged to form
 10 outer surfaces cylindrically convex about its vertical axis, and each of said side frames having a plurality of pockets, each defined by cylindri-
 cally concave surfaces, cooperating with the said faces on one of said journal boxes for hold-
 5 ing said boxes in place while allowing angling between each box and its associated side frame in a horizontal plane, and a swing motion bolster fitting over said transom-bolster and suspended therefrom by means of links mounted on the
 10 ends of keys extending therethrough, said keys each having a rolling bearing in said transom-
 bolster whereby said swing motion bolster has freedom of movement laterally with respect to said frames and said frames have freedom of
 5 movement for angling with respect to said transom-bolster and associated journal boxes.

17. A flexible railway truck comprising a pair of side frames connected by a transom-bolster spring-supported therefrom, each of said side frames being spring-supported from journal boxes slidably mounted therein, each frame having guide columns cooperating with the received end of the transom-bolster to allow for horizontal angling movement therebetween, each journal box having outwardly extending horizontal webs defined by upwardly extending flanges forming abutments for journal box springs and telescoping with depending flange portions on the associated frames, said journal boxes and frames cooperating to allow for horizontal angling therebetween, the springs supporting the transom-bolster from the frame being non-harmonic with the springs supporting the frames from the boxes, to avoid the amplification of vibrations transmitted from the associated wheels, and a lateral motion bolster fitting over said transom-bolster and suspended therefrom by means of links mounted on the ends of keys extending therethrough, to thereby permit said lateral motion bolster to have freedom of movement laterally in respect of said transom-bolster and the latter to have freedom of horizontal angling movement with respect to said frames.

18. A multi-part bolster comprising a relatively long portion adapted to have its ends supported by associated side frames and a shorter portion inverted U-shape in section and partially enclosing said long portion, each end of said shorter portion being link-supported from said long portion in order to provide for lateral motion therebetween, the supporting links being swingably mounted from the ends of keys passing through said long portion, said keys being adapted to rock with respect to said portion, and removable wear plates carried by one of said bolster parts and engaging the other.

19. A flexible railway truck comprising a pair of side frames having bolster openings defined by guide columns provided with interior surfaces cylindrically concave about the vertical axes of said frames, a multi-part bolster comprising a transom bolster having end portions resiliently supported on said side frames and received in said bolster openings, said end portions being formed

with cylindrically convex side walls engaging said concave surfaces on said guide columns to allow for horizontal angling therebetween, and a lateral motion bolster relatively shorter than said transom bolster and movably supported 5 therefrom.

20. A flexible railway truck comprising a pair of side frames, the tension members of which are pivotally connected together by a tie member, each side frame having bolster openings defined 10 by guide columns provided with interior surfaces cylindrically concave about the vertical axes of said frames, a multi-part bolster comprising a transom bolster having end portions received in said bolster opening and formed with cylindri- 15 cally convex side walls engaging said concave surfaces on said guide columns to allow for angling therebetween, a lateral motion bolster swingably supported from said transom bolster by means of links, said side frames having jaws 20 at the ends thereof, and journal boxes mounted for vertical movement within said jaws.

21. A multi-part bolster comprising a member adapted to have its ends supported by associated side frames and a relatively shorter car body 25 supporting member of substantially inverted U- shape in section and partially enclosing the adjacent portion of said side frame supported member, each end of said car body supporting member being suspended from said side frame 30 supported member by a pair of links, the links of each pair being pivotally connected adjacent their lower ends to said car body supporting member and being rockably and rotatably connected adjacent their upper ends to said side 35 frame supported member.

22. A multi-part bolster comprising a transom bolster adapted to have its ends supported by associated side frames, a lateral motion bolster supported by said transom bolster and having each end thereof comprising a pair of spaced 40 depending flanges, a key adjacent each end of and extending through apertures in said transom bolster and one of the flanges of said lateral motion bolster, the lower surface of said key intermediate the ends thereof being curved to provide 45 a rocking therebetween, links disposed between said spaced flanges and depending from the ends of said keys, and pins positioned in apertures in the lower ends of said links and spaced flanges for pivotally connecting the lateral motion bolster to said links.

23. A multi-part bolster comprising a transom bolster adapted to have its ends supported by associated side frames, a lateral motion bolster supported by said transom bolster having each end 55 thereof formed by a pair of spaced depending flanges, a key adjacent each end of and extending through apertures in said transom bolster and one of the flanges of said lateral motion bolster, the lower surface of said key intermediate the ends thereof being curved to provide a rocking therebetween, links disposed between said spaced flanges depending from the outer ends of said keys, pins extending through apertures in the 60 lower ends of said links and spaced flanges, and means secured to said lateral motion bolster for retaining said last-mentioned bolster in position.

24. A multi-part bolster comprising a transom bolster having end portions adapted to be inter- 70 posed between guide columns of associated side frames and a lateral motion bolster pivotally suspended from said transom bolster by means of links mounted on the ends of keys extending therethrough, the end portions of said transom 75

- bolster having outer surfaces cylindrically convex about the vertical axes of the side frames which are adapted to cooperate with cylindrically concave inner surfaces on said guide columns for 5 horizontal angling therebetween.
25. A multi-part bolster comprising a transom bolster having end portions adapted to be interposed between guide columns of associated side frames and a U-shaped lateral motion bolster 10 overlying and swingably suspended from said transom bolster by means of links mounted on the ends of keys extending therethrough, the end portions of said transom bolster having outer surfaces cylindrically convex about the vertical 15 axes of the side frames adapted to cooperate with cylindrically concave inner surfaces on said guide columns for horizontal angling therebetween.
26. A multi-part bolster comprising a transom bolster adapted to have its ends supported by 20 associated side frames, a wear plate positioned in said transom bolster adjacent each end thereof, keys extending through apertures in said transom bolster and superimposed upon said wear plates, swing links pivotally connected to the 25 ends of said keys and a U-shaped lateral motion bolster in straddling relation with said transom bolster and pivotally connected to said links.
27. A multi-part bolster comprising a transom bolster adapted to have its ends resiliently supported by associated side frames, a wear plate positioned in said transom bolster adjacent each 30 end thereof, keys extending through apertures in said transom bolster and bearing upon said wear plates, swing links pivotally connected to the 35 ends of said keys, and a lateral motion bolster pivotally connected to said links, the bottom surface of said keys intermediate the ends thereof being curved thereby elongating the effective radius of rotation of said links.
40. 28. In a flexible railway truck, in combination, a pair of side frames having bolster openings defined by guide columns provided with interior surfaces cylindrically concave about the vertical axes of said frames, a multi-part bolster comprising a transom bolster having end portions received in said bolster openings and formed with cylindrically convex side walls engaging said concave surfaces on said guide columns to allow for 45 angling therebetween, a lateral motion bolster swingably supported from said transom bolster by means of links, said side frames having jaws at 50 the ends thereof, journal boxes embraced between and movable vertically with respect to said jaws, and resilient means interposed between the 55 journal boxes and side frames for supporting said frames from said boxes.
29. A flexible railway truck comprising a pair of side frames, each having bolster openings defined by guide columns provided with interior 60 surfaces cylindrically concave about the vertical axes of said frames, a multi-part bolster comprising a transom bolster having end portions received in said bolster openings and formed with cylindrically convex side walls engaging said concave surfaces on said guide columns to allow for 65 horizontal angling therebetween, a lateral motion
- bolster swingably supported from said transom bolster by means of links, said side frames having jaws at the ends thereof, journal boxes between said jaws and having cylindrical convex surfaces coaxial with the vertical axes thereof, and said jaws having corresponding cylindrically concave surfaces cooperating with said journal box convex surfaces for allowing a relative horizontal angling therebetween. 5
30. A car body supporting bolster supported for lateral movement from a transom bolster, said first-mentioned bolster being substantially U-shape in section and having an upper web carrying a center bearing and having raised end portions forming side bearing supports, said upper web overlying said transom bolster, side flanges depending from the edges of said web adapted to be positioned adjacent said transom bolster, and means extending between said side flanges and bisecting the vertical plane of said transom 20 bolster for preventing accidental separation of the car body supporting and transom bolsters. 25
31. In a multi-part bolster comprising a transom bolster adapted to have its ends removably associated with spaced side frames, a lateral motion bolster substantially inverted U-shape in cross section and being of a length less than the distance between said side frames, means associated with and extending outwardly of side walls of said transom bolster, movable connecting 30 means extending between said first-named means and lateral motion bolster for rockably supporting said lateral motion bolster from said transom bolster, and means connecting side flanges of said lateral motion bolster and positioned in 35 the vertical plane of said transom bolster for preventing accidental separation of said bolster. 40
32. In a multi-part bolster comprising a transom bolster and a lateral motion bolster having its ends terminating short of said transom bolster, a key extending through apertures in said transom bolster, links depending from ends of said keys and having the lower extremities thereof pivotally connected to side flanges of said lateral motion bolster, said flanges being apertured to 45 permit insertion and removal of said key, said apertures in said flanges being normally out of horizontal alignment with said transom bolster apertures so as to prevent accidental displacement of said key. 50
33. In a vertically movable multi-part bolster, in combination, a transom bolster and a lateral motion bolster relatively shorter than said transom bolster, means interposed between said bolsters for supporting said lateral motion bolster 55 from said transom bolster, said means comprising a wear plate removably associated with said transom bolster intermediate the height thereof, and a vertically disposed member bearing upon said wear plate, said member having a lower 60 curved surface in engagement with and of less radius than a curved surface on said wear plate to thereby provide for a rocking movement of said lateral motion bolster. 65

DONALD S. BARROWS.
